UNITED STATES PATENT OFFICE.

CHARLIE E. MARK, OF CHICAGO, ILLINOIS.

APPARATUS FOR TREATING MATERIALS.

No. 846,538.

Specification of Letters Patent. Patented March 12, 1907.

Application filed September 12, 1903. Serial No. 172,862.

To all whom it may concern:

Be it known that I, CHARLIE E. MARK, a citizen of the United States of America, and a resident of Chicago, Cook county, Illinois, have invented a certain new and useful Improvement in Apparatus for Treating Materials, of which the following is a specification.

My invention contemplates a furnace having a hearth whereon any desired material may be subjected to heat and means independent of or above the hearth adapted to make direct contact with the materials being thus treated and adapted also to inject air or other gases or fluids into the materials or substances thus subjected to the heat of the furnace.

It also contemplates a furnace having a hearth whereon any desired materials may be subjected to heat and moving means adapted to agitate or treat the materials while on the hearth and adapted also at such time to inject the air or other gases or fluids into the said materials.

Also, broadly considered, my invention contemplates a furnace having a hearth whereon materials may be subjected to heat, means for agitating or stirring the materials, means for producing relative movement between the hearth and the agitating or stirring means, and means for introducing air or other gases or fluids into the materials through whichever of the said elements is given movement or motion.

The nature and advantages of my invention will, however, hereinafter more fully appear.

In the drawings, Figure 1 is a transverse section through an ore-roasting furnace embodying the principles of my invention. Fig. 2 is an enlarged side elevation of a hearth, the rabbles, and a portion of the rotary wheel or device for injecting air into the ore by way of the rabbles. Fig. 3 is a longitudinal section of one of the valves which are located in the spokes of said wheel, showing the valve closed. Fig. 4 is a view similar to Fig. 3, showing the valve open. Fig. 5 is an enlarged detail side elevation of one of the flexible joints with which the spokes of said wheel are provided. Fig. 6 is an enlarged bottom plan view of a portion of one of the hollow rabbles-bars. Fig. 7 is a diagonal cross-section taken on line 7-7, Fig. 6.

As thus illustrated the furnace, as far as general construction is concerned, can be of the usual and well-known character comprising

ing a hearth A, adapted to support the ore, side walls B, of suitable masonry, and a top wall C. The ore is fed to the hearth or body through the opening D and is caused to move or progress slowly along this hearth by the action of the rabbles E, which latter travel in the direction indicated by the arrow. Thus constructed the furnace is on the order of a reverberatory furnace, the heat being supplied in any suitable or desired manner.

In the treatment of ore sulfids, such as pulverized gold ore, it is highly desirable to stir and slowly agitate the ore while it is on the hearth and while it is being subjected to a roasting action, and experience has shown that it is also highly desirable to at such time introduce or inject air into the ore for the purpose of securing a more efficient and effective oxidizing action. As a matter of special improvement and with a view to obtaining an efficient oxidizing action the rabbles E are preferably in the form of hollow bars e, mounted on parallel chains or link belts e'. These link belts are in turn mounted, preferably, on sprocket-wheels e², and the proper movement of the rabbles from one end to the other of the hearth is obtained by applying power to one of the shafts upon which these sprocket-wheels are mounted. Preferably and in order to properly support the rabbles at the proper distance just above the surface of the hearth the chains are also provided with rolls or wheels e³, adapted to travel upon the tracks or ways e⁴. The rabbles-bars e connect the two chains and are preferably arranged at regular intervals along the latter, it being understood that any suitable or desired number of these bars can be employed and that they can be arranged either closely together or some distance apart, as conditions may require. The projections e⁵, which are secured to the rabbles-bars, constitute the means for engaging and stirring or agitating the ore, are made hollow, as shown in Fig. 7, and are provided with small openings or perforations e⁶. The interior of each projection e⁵ communicates with the interior of the bar to which it is secured, as illustrated. It is also seen that these projections or rabbles proper are preferably arranged obliquely upon the rabbles-bars, as shown in Fig. 6.

This arrangement is found to give a very satisfactory and efficient stirring or agitating action. With the rabbles proper thus made hollow and provided with small perforations air can be introduced through them into the

ore during the operation of roasting. Thus while the rabbles are traveling slowly through the ore, so as to not only agitate and stir the ore, but also cause the slow and steady progressive movement of the ore over the surface of the hearth and moving of the ore along the hearth, these rabbles are at the same time serving as a means for introducing the air into the heated body of ore. In other words, the rabbles have a double function—to wit, the stirring and agitating of the ore and the injection of air into the ore. By thus combining the rabbling and the air-injecting means into one unitary structure a very efficient and satisfactory oxidizing action is obtained.

It is obvious that any suitable, known, or approved means can be employed for connecting the hollow rabbles with a suitable source of air-pressure. For example and as illustrated, the arrangement involves a rotary wheel having the hollow spokes F and the hollow hub f , the spokes at their ends being adapted to engage the openings e' in the outer ends of the rabble-bars. Air is supplied under pressure to the hub of this wheel, and this pressure is then communicated to the hollow rabbles as fast as the ends of the spokes F engage the ends of the hollow rabble-bars. With this arrangement the said spokes are preferably composed of telescoping tubes held normally distended by springs f' . This provision permits the spokes to slowly contract and telescope during the first part of their connection with the rabble-bars and to then slowly lengthen during the latter part of their connection with the rabble-bars and before being disconnected from the latter. It is also preferable with an arrangement of this character to provide each spoke with a flexible joint f'' and to connect the different spokes by means of springs f''' . In this way there is no binding or cramping during the engagement of the spokes with the rabble-bars, the said flexible joints permitting the desired amount of relative movement between the spokes actually engaging the rabble-bars, and the said springs then tending to restore the spokes to their normal positions after being disengaged or disconnected from the rabbles. As a matter of further and special improvement each spoke is also preferably provided with an automatic valve device, whereby air can only pass outwardly through the spokes after they have been telescoped or shortened to a certain extent. A simple valve arrangement for this purpose is shown in Figs. 3 and 4. As thus illustrated, the valve comprises the apertured upper end f^4 of the lower or smaller tube of the spoke and the lower end f^5 of the outer and larger tube of the spoke. Normally the spring f'' keeps the tubes in the relative positions shown in Fig. 3, the tube f^5 closing the apertured tube portion f^4 .

Upon a slight telescoping or shortening of the spoke it will be seen that the upper and larger tube having the lower end portion f^5 slides downwardly upon the smaller tube, thereby uncovering the apertures in the tube portion f^4 and in this way establishing communication between the interior of the smaller tube and the interior of the larger tube. Thus in this way each rabble-bar after engaging the spoke forces the larger and outer tube downwardly to an extent to automatically open the normally closed valve in the spoke and to in this way automatically establish communication between the hollow hub of the wheel and the interior of the rabbles. In other words, the air cannot escape from the rotary wheel except when properly engaged by the rabble-bars. The air-pressure thus communicated to the interior of the rabbles through the hollow spokes of the wheel and through the hollow rabble-bars then escapes through the openings e' into the heated body of ore. It is obvious that any other suitable or desired arrangement can be employed for connecting the rabbles with the source of air-pressure and for automatically controlling the same.

It will be readily understood that any other suitable arrangement can be employed for producing a relative movement between the rabbles and the bed or hearth of the furnace. Whatever the arrangement, however, it will be seen that the air is preferably and desirably introduced into the ore through the moving elements of the furnace. Preferably, though not necessarily, these moving elements consist of the traveling rabbles, and consequently I find it preferable to introduce the air through these rabbles into the ore. Again, it will be seen that in the preferred embodiment of my invention the arrangement for introducing the air into the heated body of ore is wholly independent of the hearth or body of the furnace and is preferably above the hearth and of such nature as to project downwardly and into the ore. It will also be understood that my invention is applicable to furnaces of various kinds and to the treating of various materials other than ore or metals. For example, the more specific contemplation of my invention, which consists in employing the stirring or agitating means as the means for introducing the air or other fluid into the materials to be treated, is obviously applicable to various processes and to the treatment of various materials and to various methods of manufacture.

I claim as my invention—

1. An apparatus for treating granular or comminuted materials, comprising a suitable support for said materials and a moving member adapted for both agitating and injecting fluids into said materials together with suitable provisions for introducing the ore

or other materials to be treated, and for withdrawing the same, and means for subjecting the ore or other materials to heat while subject to the action of the said combined agitating and fluid-injecting means operated by endless chains.

2. Apparatus for treating granular or comminuted materials, comprising means for supporting and agitating said materials, said means including a movable member through which fluids are injected into said materials together with suitable provisions for introducing the ore or other materials to be treated, and for withdrawing the same, and means for subjecting the ore or other materials to heat while subject to the action of the said combined agitating and fluid-injecting means operated by endless chains.

3. Apparatus for treating granular or comminuted materials, comprising means for supporting, heating, and agitating materials, said means including a movable member through which fluids are injected into the said materials together with suitable provisions for introducing the ore or other materials to be treated, and for withdrawing the same, and means for subjecting the ore or other materials to heat while subject to the action of the said combined agitating and fluid-injecting means operated by endless chains.

4. A furnace having a suitable hearth for supporting granular or comminuted materials, a hollow agitating device adapted to be given movement directly above the hearth, so as to agitate whatever materials are to be treated on said hearth, and suitable devices for connecting said agitating device with a source of fluid-pressure together with suitable provisions for introducing the ore or other materials to be treated, and for withdrawing the same, and means for subjecting the ore or other materials to heat while subject to the action of the said combined agitating and fluid-injecting means operated by endless chains.

5. A furnace having a suitable hearth for supporting granular or comminuted materials, a hollow agitator adapted to be given movement directly above the hearth, so as to agitate the materials which are to be treated on said hearth, and suitable devices for connecting said agitator with a source of air-pressure together with suitable provisions for introducing the ore or other materials to be treated, and for withdrawing the same, and means for subjecting the ore or other materials to heat while subject to the action of the said combined agitating and fluid-injecting means operated by endless chains.

6. A roasting-furnace having a suitable hearth, hollow rabbles having outlets and adapted to be operated in any suitable manner, and suitable devices for connecting said rabbles with a source of air-pressure together with a pair of parallel endless chains for oper-

ating the rabbles together with suitable provisions for introducing the ore or other materials to be treated, and for withdrawing the same, and means for subjecting the ore or other materials to heat while subject to the action of the said combined agitating and fluid-injecting means.

7. A roasting-furnace having a suitable hearth, means for rabbling and introducing air into the body of ore resting on the hearth, said means including air-injecting devices which are independent of and arranged immediately above the hearth, and a suitable arrangement for connecting the said air-injecting devices with a source of air-pressure together with a pair of parallel endless chains for operating the rabbles together with suitable provisions for introducing the ore or other materials to be treated, and for withdrawing the same, and means for subjecting the ore or other materials to heat while subject to the action of the said combined agitating and fluid-injecting means.

8. A roasting-furnace comprising means for supporting, rabbling, and injecting air into the ore, said means including a movable member through which the air is injected into the ore together with a pair of parallel endless chains for operating the rabbles together with suitable provisions for introducing the ore or other materials to be treated, and for withdrawing the same, and means for subjecting the ore or other materials to heat while subject to the action of the said combined agitating and fluid-injecting means.

9. A roasting-furnace having a suitable hearth, hollow rabbles provided with outlets and adapted to be operated in any suitable manner, a source of air-pressure, and means including automatically-operated valves for connecting said rabbles with the source of air-pressure together with a pair of parallel endless chains for operating the rabbles together with suitable provisions for introducing the ore or other materials to be treated, and for withdrawing the same, and means for subjecting the ore or other materials to heat while subject to the action of the said combined agitating and fluid-injecting means.

10. A roasting-furnace comprising a hearth for supporting the ore, a pair of parallel endless chains, fluid-delivering rabbles carried and operated by said chains, and means for supplying air to said rabbles.

11. An apparatus for treating granular or comminuted materials, comprising a suitable support for said materials, and a moving member adapted for both agitating and injecting fluids into said materials, together with suitable provisions whereby the combined agitating and fluid-injecting means thus provided is alternately connected with and disconnected from the source of air or other fluid pressure.

12. Apparatus for treating granular or

- comminuted materials, comprising means for supporting, heating and agitating materials, said means including a movable member through which fluids are injected into the 5 said materials, together with suitable provisions whereby the combined agitating and fluid-injecting means thus provided is alternately connected with and disconnected from the source of air or other fluid pressure.
13. A furnace having a suitable hearth for supporting granular or comminuted materials, a hollow agitating device adapted to be given movement directly above the hearth, so as to agitate whatever materials are to be 10 treated on said hearth, and suitable devices for connecting said agitating device with a source of fluid-pressure, together with suitable provisions whereby the combined agitating and fluid-injecting means thus provided is alternately connected with and disconnected from the source of air or other fluid pressure.
14. A roasting-furnace having a suitable hearth, hollow rabbles having outlets and 15 adapted to be operated in any suitable manner, and suitable devices for connecting said rabbles with a source of air-pressure, together with power-transmitting connections for operating the rabbles, and suitable provisions whereby the combined agitating and fluid-injecting means thus provided is alternately connected with and disconnected from the source of air or other fluid pressure.
15. A roasting-furnace having a suitable hearth, means for rabbling and introducing air into the body of ore resting on the hearth, said means including air-injecting devices which are independent of and arranged immediately above the hearth, a suitable arrangement for connecting the said air-injecting devices with a source of air-pressure, and suitable provisions whereby the combined agitating and fluid-injecting means thus provided is alternately connected with and disconnected from the source of air or other fluid pressure.
16. A roasting-furnace comprising means for supporting, rabbling and injecting air into the ore, said means including a movable member through which the air is injected into the ore, together with power-transmitting connections for operating the rabbles, and suitable provisions whereby the combined agitating and fluid-injecting means thus provided is alternately connected with and disconnected from the source of air or other fluid pressure.
17. A roasting-furnace having a suitable hearth, hollow rabbles provided with outlets and adapted to be operated in any suitable manner, a source of air-pressure, and means including automatically-operated valves for connecting said rabbles with the source of air-pressure, together with power-transmitting connections for operating the rabbles,
- and suitable provisions whereby the combined agitating and fluid-injecting means thus provided is alternately connected with and disconnected from the source of air or other fluid pressure.
18. A roasting-furnace comprising a hearth for supporting the ore, a pair of parallel endless chains, fluid-delivering rabbles carried and operated by said chains, and means for supplying air to said rabbles, together with suitable provisions whereby the combined agitating and fluid-injecting means thus provided is alternately connected with and disconnected from the source of air or other fluid pressure.
19. A roasting-furnace provided with fluid-delivering mechanical rabbles, together with suitable provisions whereby the combined agitating and fluid-injecting means thus provided is alternately connected with and disconnected from the source of air or other fluid pressure.
20. A roasting-furnace comprising a hearth and one or more fluid-delivering mechanical rabbles, substantially as shown and described, agitating and fluid-injecting means, together with suitable provisions whereby the combined agitating and fluid-injecting means thus provided is alternately connected with and disconnected from the source of air or other fluid pressure.
21. An apparatus for treating granular or comminuted materials, comprising a suitable support for said materials, and a moving member adapted for both agitating and injecting fluids into said materials, together with suitable provisions whereby the combined agitating and fluid-injecting means thus provided is connected with the source of air or other fluid pressure for only a portion of its path of travel through the ore or other materials being treated.
22. A furnace having a suitable hearth for supporting granular or comminuted materials, a hollow agitating device adapted to be given movement directly above the hearth, so as to agitate whatever materials are to be treated on said hearth, and suitable devices for connecting said agitating device with a source of fluid-pressure, together with suitable provisions whereby the combined agitating and fluid-injecting means thus provided is connected with the source of air or other fluid pressure for only a portion of its path of travel through the ore or other materials being treated.
23. A roasting-furnace provided with fluid-delivering mechanical rabbles, together with suitable provisions whereby the combined agitating and fluid-injecting means thus provided is connected with the source of air or other fluid pressure for only a portion of its path of travel through the ore or other materials being treated.
24. A roasting-furnace comprising a hearth

and one or more fluid-delivering mechanical rabbles, substantially as shown and described, agitating and fluid-injecting means, together with suitable provisions whereby the combined agitating and fluid-injecting means thus provided is connected with the source of air or other fluid pressure for only a portion of its path of travel through the ore or other materials being treated.

25. An apparatus for treating granular or comminuted materials, comprising a suitable support for said materials, and a moving member adapted for both agitating and injecting fluids into said materials, together with suitable provisions whereby the combined agitating and fluid-injecting means thus provided receives air or other fluid through a rotary wheel-like member adapted to have the ends of its hollow spokes successively connected with the said means.

26. Apparatus for treating granular or comminuted materials, comprising means for supporting, heating and agitating materials, said means including a movable member through which fluids are injected into the said materials, together with suitable provisions whereby the combined agitating and fluid-injecting means thus provided receives air or other fluid through a rotary wheel-like member adapted to have the ends of its hollow spokes successively connected with the said means.

27. A furnace having a suitable hearth for supporting granular or comminuted materials, a hollow agitating device adapted to be given movement directly above the hearth, so as to agitate whatever materials are to be treated on said hearth, and suitable devices for connecting said agitating device with a source of fluid-pressure, together with suitable provisions whereby the combined agitating and fluid-injecting means thus provided receives air or other fluid through a rotary wheel-like member adapted to have the ends of its hollow spokes successively connected with the said means.

28. A roasting-furnace having a suitable hearth, hollow rabbles having outlets and adapted to be operated in any suitable manner, and suitable devices for connecting said rabbles with a source of air-pressure, together with power-transmitting connections for operating the rabbles, together with suitable provisions whereby the combined agitating and fluid-injecting means thus provided receives air or other fluid through a rotary wheel-like member adapted to have the ends of its hollow spokes successively connected with the said means.

29. A roasting-furnace having a suitable hearth, means for rabbling and introducing air into the body of ore resting on the hearth, said means including air-injecting devices which are independent of and arranged immediately above the hearth, and a suitable

arrangement for connecting the said air-injecting devices with a source of air-pressure, together with power-transmitting connections for operating the rabbles, and suitable provisions whereby the combined agitating and fluid-injecting means thus provided receives air or other fluid through a rotary wheel-like member adapted to have the ends of its hollow spokes successively connected with the said means.

30. A roasting-furnace comprising means for supporting, rabbling and injecting air into the ore, said means including a movable member through which the air is injected into the ore, together with power-transmitting connections for operating the rabbles, and suitable provisions whereby the combined agitating and fluid-injecting means thus provided receives air or other fluid through a rotary wheel-like member adapted to have the ends of its hollow spokes successively connected with the said means.

31. A roasting-furnace having a suitable hearth, hollow rabbles provided with outlets and adapted to be operated in any suitable manner, a source of air-pressure, and means including automatically-operated valves for connecting said rabbles with the source of air-pressure, together with power-transmitting connections for operating the rabbles, together with suitable provisions whereby the combined agitating and fluid-injecting means thus provided receives air or other fluid through a rotary wheel-like member adapted to have the ends of its hollow spokes successively connected with the said means.

32. A roasting-furnace comprising a hearth for supporting the ore, a pair of parallel endless chains, fluid-delivering rabbles carried and operated by said chains, and means for supplying air to said rabbles, together with suitable provisions whereby the combined agitating and fluid-injecting means thus provided receives air or other fluid through a rotary wheel-like member adapted to have the ends of its hollow spokes successively connected with the said means.

33. A roasting-furnace comprising a hearth and one or more fluid-delivering mechanical rabbles, substantially as shown and described, agitating and fluid-injecting means, together with suitable provisions whereby the combined agitating and fluid-injecting means thus provided receives air or other fluid through a rotary wheel-like member adapted to have the ends of its hollow spokes successively connected with the said means.

34. Apparatus for treating granular or comminuted materials, comprising means for supporting and agitating said materials, said means including a movable member through which fluids are injected into the said materials, together with suitable provisions whereby the said combined agitating

and fluid-injecting means passes through the ore or other materials for only a portion of its path of travel.

35. Apparatus for treating granular or comminuted materials, comprising means for supporting, heating and agitating materials, said means including a movable member through which fluids are injected into the said materials, together with suitable provisions whereby the said combined agitating and fluid-injecting means passes through the ore or other materials for only a portion of its path of travel.

36. A furnace having a suitable hearth for supporting granular or comminuted materials, a hollow agitator adapted to be given movement directly above the hearth, so as to agitate the materials which are to be treated on said hearth, and suitable devices for connecting said agitator with a source of air-pressure, together with suitable provisions whereby the said combined agitating and fluid-injecting means passes through the ore or other materials for only a portion of its path of travel.

37. A roasting-furnace having a suitable hearth, hollow rabbles having outlets and adapted to be operated in any suitable manner, and suitable devices for connecting said rabbles with a source of air-pressure, together with power-transmitting connections for operating the rabbles, and suitable provisions whereby the said combined agitating and fluid-injecting means passes through the ore or other materials for only a portion of its path of travel.

38. A roasting-furnace having a suitable hearth, means for rabbling and introducing air into the body of ore resting on the hearth, said means including air-injecting devices which are independent of and arranged immediately above the hearth, and a suitable arrangement for connecting the said air-injecting devices with a source of air-pressure, together with power-transmitting connections for operating the rabbles, and suitable provisions whereby the said combined agitating and fluid-injecting means passes through the ore or other materials for only a portion of its path of travel.

39. A roasting-furnace comprising means

for supporting, rabbling and injecting air into the ore, said means including a movable member through which the air is injected into the ore, together with power-transmitting connections for operating the rabbles, and suitable provisions whereby the said combined agitating and fluid-injecting means passes through the ore or other materials for only a portion of its path of travel. 55

40. A roasting-furnace having a suitable hearth, hollow rabbles provided with outlets and adapted to be operated in any suitable manner, a source of air-pressure, and means including automatically-operated valves for connecting said rabbles with the source of air-pressure, together with power-transmitting connections for operating the rabbles, and suitable provisions whereby the said combined agitating and fluid-injecting means 60 passes through the ore or other materials for only a portion of its path of travel.

41. A roasting-furnace comprising a hearth for supporting the ore, a pair of parallel endless chains, fluid-delivering rabbles carried 75 and operated by said chains, and means for supplying air to said rabbles, together with suitable provisions whereby the said combined agitating and fluid-injecting means passes through the ore or other materials for 80 only a portion of its path of travel.

42. A roasting-furnace comprising a hearth and one or more fluid-delivering mechanical rabbles, substantially as shown and described, 85 agitating and fluid-injecting means; together with suitable provisions whereby the said combined agitating and fluid-injecting means passes through the ore or other materials for only a portion of its path of travel.

43. In a roasting-furnace, the combination 90 of hollow rabbles, a source of air-pressure, and means for automatically and alternately connecting the rabbles with the source of air-pressure and disconnecting the same therefrom. 95

Signed by me at Chicago, Cook county, Illinois, this 4th day of September, 1903.
